DESIGN FOR A CLOCK DIAL OR SIMILAR ARTICLE

Lucien Ribera, New York, N. Y.

Application June 15, 1935, Serial No. 57,281

Term of patent 14 years

To all whom it may concern:

Be it known that I, Lucien Ribera, a citizen of the United States, residing at New York, in the county and State of New York, have invented a new, original, and ornamental Design for a Clock Dial or Similar Article, of which the following is a specification, reference being had to the accompanying drawing, forming a part thereof.

The figure is a plan view of a clock dial or similar article, showing my new design.

The design has no appreciable thickness.

I claim:

The ornamental design for a clock dial or similar article substantially as shown and described.

LUCIEN RIBERA.
